P. WEINHOLT.

TOY PISTOL.

APPLICATION FILED MAR. 20, 1919.

1,311,934.

Patented Aug. 5, 1919.

13 Inventor:
A Paul Weinholt,
By George A. Pennington
his Atty.

UNITED STATES PATENT OFFICE.

PAUL WEINHOLT, OF ST. LOUIS, MISSOURI, ASSIGNOR OF ONE-HALF TO OSCAR GEORGE KOSTEDT, OF ST. LOUIS, MISSOURI.

TOY PISTOL.

1,311,934.

Specification of Letters Patent.

Patented Aug. 5, 1919.

Application filed March 20, 1919. Serial No. 283,752.

To all whom it may concern:

Be it known that I, PAUL WEINHOLT, a citizen of the United States, residing in the city of St. Louis and State of Missouri, have 5 invented a new and useful Improvement in Toy Pistols, of which the following is a specification.

This invention relates to toy guns and more particularly to a pistol structure. It 10 has for its objects to produce a novel construction which is simple and inexpensive to manufacture, which is efficient and durable, and which may be made to simulate a regular firearm; and to attain certain advantages 15 as will hereinafter more fully appear.

The invention consists in the parts and in the combinations and arrangements of parts as set forth in the following description and afterward pointed out with particularity in 20 the appended claims.

In the accompanying drawing illustrating a practical embodiment of the invention,—

Figure 1 is a view of a toy pistol in side elevation;

Fig. 2 is a longitudinal section thereof with the plunger in retracted position;

Fig. 3 is a similar view with the plunger projected;

Fig. 4 is a cross section taken on or about 30 the line 4—4 of Fig. 1;

Fig. 5 is a cross section taken on or about the line 5—5 of Fig. 1; and

Fig. 6 is a detail view of the spring member detached and in relaxed condition.

Referring now to the drawing, the structure therein shown comprises a barrel 1, the breech portion 2 of which is tubular and cylindrical, while the forward portion 3 is trough-like or substantially U-shape in cross section (see Figs. 4 and 5). The handle portion 4 is hollow and flattened to a thickness less than the diameter of the barrel.

Fitted slidably in the barrel 1 is a plunger 5. Preferably, this plunger comprises a hol-

45 low cylinder which is closed at its outer end, as at 6, so as to bear against a projectile, which latter may obviously be a ball 7, as shown in Fig. 2, or a stick, dart, or other suitable object capable of being placed in 50 and movable freely through the barrel or channel 3.

Located in the handle portion 4 is a spring member 8 which is preferably coiled intermediate its ends, as at 9. One leg, 10, of the 55 spring member is engaged in an aperture 11

in the under side of the plunger 5 near the rear end thereof, and the end portion 12 of this leg which projects into the plunger is preferably curved forwardly as shown.

The opposite leg 13 of the spring member 60 is curved, as at 14, so as to seat against the crotched portion 15 of the rear wall of the handle 4, thence rebent and extended straightwise, as at 16, and then again rebent to form a projection or hook 17 to engage 65 in a slot or other suitable aperture 18 in the under part of the plunger 5 near the outer end thereof. From this hook portion 17 the wire is extended straightwise, as at 19, and rebent upon itself, as at 20, to constitute a 70 trigger.

The trigger is projected through a restricted opening or slot 21 which is provided by eliminating a part of the bottom wall between the barrel and handle and depressing 75 the adjacent side walls, as at 22, so as to afford a lateral support and guide for the trigger and hook portion, but with sufficient clearance between to permit an easy up and down movement of the wire to effect the engagement and release of the hook and the plunger 5.

The normal set or relaxed shape of the spring member when detached from the pistol is shown in Fig. 6. In this normal or relaxed condition the entire two legs 10 and 13 are spread apart and the portion 16 of the leg 13 is set at an obtuse angle to the base portion thereof. Therefore, when the spring member is assembled in the pistol, as shown 90 in Fig. 2, under tension, the tendency of the spring is to assume its normal form, so that the leg 10 is constantly acting to press the plunger forward, while the leg 13 is bearing against the rear wall of the handle portion 95 4 and the portion 16 of the spring member is pressing toward the under side of the plunger so as to engage the hook 17 with the plunger.

When it is desired to project the plunger, 100 the trigger is pulled to disengage the hook 17 therefrom, whereupon the leg 10 of the spring member moves suddenly forward, carrying the plunger with it, until it is arrested by the front wall of the handle portion 4. When thus arrested the leg 10 limits the outward travel of the plunger and thereby serves the dual function of motive element and stop. The stopping of the plunger is not brought about abruptly, but 110

there is a slight over-travel and rebound to the position of rest, due to the momentum and resiliency of the leg 10. This serves as a cushion to some extent, and to effectively 5 whip the projectile from the barrel or channel 3.

To reset the parts for another actuation of the plunger it is only necessary to insert the finger in the channel 3 and press the 10 plunger back until the hook 17 snaps into the aperture 18 thereof.

The body of the pistol may be conveniently and inexpensively constructed of tin or other suitable sheet material in die- 15 pressed and formed blanks, either single or in plurality, the meeting edges of which may be seamed by folding or otherwise securing them together. This is the preferable kind of structure, but it may be made 20 of cast metal, as is obvious.

The device admits of considerable modification without departing from the spirit of the invention as defined by the appended claims. Therefore, it is not limited to the 25 specific construction shown in the drawing.

What is claimed is:

1. In a toy pistol, a barrel in which is housed a plunger, the forward portion of the barrel being channeled from the region 30 of the outer end portion of said plunger in its retracted position to the outer end of the barrel.

2. In a toy pistol, a barrel, the inner portion of which is tubular and the outer portion 35 of which is channeled, a spring-pressed plunger in said barrel, the spring for actuating said plunger serving as a stop therefor, and having an extension formed to afford a catch to hold the plunger retracted, 40 the extreme end portion of said extension constituting a trigger.

3. In a toy pistol, a barrel and communi-

cating hollow handle extension, a plunger in said barrel, and a single-piece spring having oppositely-acting legs, one of said legs engaging said plunger to press it forward and being engageable with a forward part of said handle extension to afford a stop for said plunger when actuated thereby, the other leg being engageable with a rear part 45 of said handle extension and a portion thereof being formed to afford a catch to engage and hold said plunger in retracted position, and the extreme end portion of said leg being arranged to constitute a trigger. 50

4. In a toy pistol, a barrel and communicating hollow handle extension, a tubular plunger in said barrel, said plunger having an aperture in its under side near its rear 60 end and a second aperture likewise near its outer end, a single-piece spring having two oppositely-acting legs, one of said legs being engaged in the aperture at the rear of said plunger and acting to drive the plunger 65 forward and being engageable with the forward part of said handle extension to afford a stop for said plunger when actuated, the other leg having a portion in engagement with the rear part of said handle 70 extension, another portion extended lengthwise and in proximity to the under side of said plunger, with a catch portion to engage in the aperture at the front of said plunger, the extreme end portion of said leg 75 constituting a trigger and projecting through a slot between the bottom of the barrel and said handle extension, the adjacent side walls being depressed in proximity to and affording a guide for said catch portion 80 and trigger portion of the spring.

Signed at St. Louis, Missouri, this 8th day of March, 1919.

PAUL WEINHOLT.
